UNITED STATES PATENT OFFICE.

CHARLES K. HALL AND WILLIAM B. LILLARD, OF NEW ORLEANS, LOUISIANA.

ELECTRICAL ALARM SYSTEM.

SPECIFICATION forming part of Letters Patent No. 504,980, dated September 12, 1893.

Application filed November 2, 1892. Serial No. 450,776. (No model.)

To all whom it may concern:

Be it known that we, CHARLES K. HALL and WILLIAM B. LILLARD, citizens of the United States, residing at New-Orleans, in the parish 5 of Orleans and State of Louisiana, have invented certain new and useful Improvements in Electrical Alarm Systems; and we do hereby declare the following to be a full, clear, and exact description of the invention, such 10 as will enable others skilled in the art to which it appertains to make and use the same.

This invention relates to electric alarms and signals, and is specially designed to provide a cheap and reliable alarm system for use 15 in factories, stores, private houses, and in such places generally where either fire alarms or burglar alarms or both are desirable, or where signals are to be made.

The invention also consists in certain novel 20 features forming part of, or capable of being adapted to use in the system as a whole.

Reference is had to the accompanying drawings, wherein the same parts are indicated by the same letters and numerals throughout the 25 several views.

Figure 1 represents a perspective view, parts being broken away, of a central office connected to three houses employing the hereinafter described system of alarms, the electrical 30 connection in two of the said houses being shown diagrammatically. Fig. 1^a represents a diagrammatic view of the circuits shown in Fig. 1. Fig. 2 represents an improved switch which may be used in connection with the 35 leading-in wires to each house or station. Fig. 3 represents a plan view of the improved circuit closing device, which may be used with this system for sounding a burglar alarm. Fig. 4 represents a perspective view of a window 40 fitted with this contact making device to sound a burglar alarm. Fig. 5 represents a perspective view of a portion of a door fitted with the said contact-making device to sound a burglar alarm. Fig. 6 represents a side elevation of an improved thermostat adapted to 45 be used with the system.

The system consists essentially of an all metallic circuit open at both ends, with the arrangement of signals and alarms hereinafter described.

In each house, factory, &c., there are two continuous wires insulated from each other

except that each of said wires is connected to one terminal of a source of electricity, preferably a battery or cell, and included in each 55 of the bridges thus formed is an alarm bell, indicator or other apparatus for signaling. The two terminals of a thermostat may also be joined to each of the wires, or the two wires after being insulated with combustible 60 material may be wrapped together thus forming a thermostat, as described in the patent to Kitsee, No. 262,056, granted August 1, 1882. Electrical connection made anywhere between the two wires, will then ring all the alarms 65 whose terminals are connected thereto.

In Fig. 1 are shown three houses indicated by H', H² and H³, which are connected to a central office, by wires 1, 2 and 3, one to each building, and by a general return wire R connected to all the buildings. This return wire R may be supplanted by a return circuit through the earth as indicated in dotted lines at R', R², and R³, in which case only one leading in wire to each house would be required. 70 But since each house or group of houses is adapted to make its various signals and alarms independent of the central station, the connections in each house will first be described 75 and then the connections from the house to the central station.

In the house H' the wires r¹¹, r¹², r¹³, r¹⁴ and r¹⁵ are in continuous connection, while parallel to these wires and also in continuous connection with each other, are the wires 11, 12, 13, 85 14 and 15. These two groups of wires r¹¹ to r¹⁵, and 11 to 15, may each be considered as one continuous wire, and equivalent to the wires r³¹ and 31 shown in the house H³.

In the house H' the wires 11 and r¹¹ are provided with a double switch S or other suitable device for connecting the two wires to the central station as will be hereinafter described, but the said double switch is represented as being open, and therefore the two groups of 95 wires in the house H' are in no way connected to the central station, and the system in the said house is entirely independent of anything outside of it. The battery C has one of its terminals connected to the wire r¹¹, and the other terminal is connected by a wire 100 passing through the bell B and switch S², hereinafter to be more fully described, to the wire 11.

Between the wires of each group, in as many places as may be desired, thermostats of that class which depend upon heat to close the circuit may be placed. Three of these thermostats, indicated by A, A' and A'', are shown in the house H', but any desired number may be used.

Between the wires r^{13} and 13, on the second floor of the house H', the battery C', electric bell B', contact piece s⁴, and switch S³ are provided. In the same way on the third floor the battery C², bell B² and switch S⁴, put the two wires in electrical connection.

The number of batteries, bells and switches on each floor or between the same two groups of wires on several floors, may be varied at will.

It will be seen by inspection of the system of wires shown in the house H', that if the two groups of wires be electrically connected at any point, every bell on the circuit will ring. Thus suppose the thermostat A' on the second floor to close the circuit as indicated in dotted lines at a', as will happen in case of fire. The current from the battery C' would go through the wire c', the bell B', contact piece s⁴, switch S³, wire 13, thermostat A', wire r^{13} and wire c³, thus ringing the bell B', or making such other signal as may be placed in the circuit instead of or in addition to the said bell. In the same way the current from the battery C² would pass through the bell B², switch S⁴, wire 14, wire 13, thermostat A', wire r^{13} , wire r^{14} , and back to the battery C². In the same way the battery C would ring its own bell, and all the bells on the circuit would keep ringing as long as the circuit was complete. Now should it be desired to call up a foreman or other person for whom a pre-established signal had been agreed upon, say to the third floor, the person signaling on the third floor would swing the switch S⁴ over to the position shown in dotted lines. The bell B² would be thrown out of circuit, and will not ring, but the circuit being closed with respect to all the other bells, all the bells on the circuit except the bell B² will ring, and any desired signal may be made to all parts of the establishment. Should it be desired that the person signaling should ring his own bell, a device like that shown in the lower story of either of the houses H' or H³ might be employed.

In the house H' the switch S², shown in enlarged plan in Fig. 2, is electrically connected to the wire 11, and may be brought into contact with the contact piece s⁵, connected to the wire r^{11} , thus cutting out the bell B. Or the contact piece s⁹ may be moved so as to also make contact with the switch S². This contact piece is pivoted at s¹⁰, and is provided with a slot s¹¹ in which the clamp screw s¹² engages. The pivot s¹⁰ is electrically connected by the conducting wire or strip s⁸ to the binding post s⁶ which is connected to the wire leading through the bell and through the battery. It will be seen that when the switch

S² makes connection with both the contact pieces s⁹ and s⁵, the circuit will be closed through the bell B as well as through all the other bells B', B², &c. The same result is accomplished by the device shown on the lower floor of the house H³, where S⁸ is an ordinary push button, and S⁷ is a switch normally closing the connection between the bell B³ and the wire 31. If the operator wishes to ring his own bell, as well as all the others on the circuit, he does not touch the switch S⁷ but merely presses the push button S⁸, when his own bell, and all the other bells in the circuit will ring. But if he wishes to cut out his own bell he should before touching the push button, open the switch S⁷, as indicated in dotted lines.

In the arrangement of the system shown in the house H³ the bells, batteries and switches form a bridge between the wires 31 and r^{31} , and thermostats are placed between these two wires as described with reference to the house H'. It will be seen by inspection of the figure that if the circuit be closed between the two wires as by the burglar alarm D, all the bells will ring.

While bells have been referred to, any other form of electric signal, such as an indicator, might be adopted in place of the bells, or in addition thereto.

Having thus described the connection in the two houses, it is purposed to explain how the said houses may be connected to or cut off from a central station or main office. There is one leading in wire connecting each house with the central station, and indicated by 1, 2, and 3, respectively. Where an all metallic circuit is used there is one return wire R for all the houses with separate leading in wires r' , r^2 , and r^3 , leading from the main return wire R into each house, and insulated from the wire 1, 2, or 3, as the case may be. It will be evident that this return wire R may be supplanted by the earth, and that only one wire be led into each house from the central station, and connection be made with the earth from the houses as at R' and R³, and from the central station as at R⁴. Assuming, however, that there is an all metallic circuit, the leading in wires 1 and r' , 3 and r^3 , &c., are connected to double switches S and S' respectively, at the binding posts s'. The arms s of these switches are joined together by an insulating piece s² having a hand knob or button s⁸, and the said arms s are adapted to be thrown in and out of contact with the contact strips s⁴ attached to the wires 11 and r^{11} , or 31 and r^{31} respectively. In Fig. 1 the switch S is represented as being out of contact with the said contact strips, and therefore the apparatus in the house H' is cut off from the central station, while the double switch S' is represented as making the connection from the house H³ to the central station, and therefore the various signals made in the said house would be repeated in the central station.

The central station is provided with a switch

board E of the ordinary type, having binding posts e and contact plugs e' with bells or annunciators, or both, marked to correspond with the house to which it is connected, for instance 1^h , 2^h , 3^h , &c. Each of said bells or annunciators is provided with a battery C^{11} , C^{12} , or C^{13} , and with a cut out switch S^3 , and wires r^{37} and 37 , r^{27} and 27 , r^{17} and 17 leading to the switchboard as shown. Now suppose the connections be made as in the house H^3 , and a burglar connect the wires r^{31} and 31 , as by raising the window F. The bells in the house H^3 will all ring as hereinbefore described, while the current from the battery C^{13} will pass through the bell and indicator 3^h showing the number of the house and sounding the alarm, down through the switch S^3 and wire 37 , to wire 3 , and switch S' , through wire 31 , the burglar alarm contact making device and its connecting wires, back to the wire r^{31} and double switch S' , then through the wire r^3 and return wire R to the switch board, then down to the wire r^{37} and back to the opposite pole of the battery C^{13} . Thus it will be seen that a contact made in the building H^3 will not only sound an alarm throughout that building, but will signal to the central office that something is wrong in the said house.

Should it be desired to call up the central office from the house H^3 , the switch S^5 or any other of the switches, or the push button S^8 may be used to make any desired number of short rings. In the same way the switch S^3 in the central office may be used to make a number of short rings or other prearranged calls in the house H^3 .

It will be seen that in this system the apparatus in each house is capable of being operated in connection with, or entirely independent of the main or central office. It will also be seen that by cutting out each house during the day, any desired calls might be made over that house without signaling to the central station, and that at night by connecting with the central station the apparatus may be used both as a burglar and fire alarm, and also be used by watchman to notify central that he is awake and on duty.

By having the apparatus in frequent use for signaling, any defects in the operative parts will be speedily discovered and can be remedied, and this feature renders the system of special advantage over those burglar and fire alarm systems wherein the batteries, wires, &c., remain idle until the emergency occurs, when through disintegration, accident, or other causes they may fail to operate.

It will readily be seen that this system is specially applicable to large factories of every description where it is desired to summon foremen and others frequently during the day-time, and to provide alarms against fire and burglars at night. In such factories the various shops may be connected to the man-

ger's office just as the houses H' , H^2 and H^3 are connected to the central office in Fig. 1.

While any form of contact-making device would be suitable for use as a burglar alarm, the special form shown in Figs. 3, 4, and 5 is preferred in combination with this system. This form consists of a contact making device D preferably attached to the frame of the door or window, and a contact breaking device D' preferably attached to the door or to the window. The part D consists of an insulating block d having one or more holes d' for screwing the same to the woodwork. To the sides of this block the metal springs d² are attached by screws d³, which also clamp the wires 35 and r³⁵ in contact with the said metal springs d². A metallic spring plunger d⁴ passes through a hole in the block and is normally pressed forward by the spring d⁵. The insulating block D' is provided with a wedge d¹⁰, and is fastened to the door or window by a screw through the hole d¹¹, or in any other convenient way. When this wedge tongue d¹⁰ is pressed between the springs d² as in closing the door or shutting the window, the spring plunger d⁴ is pressed back and the springs d² are insulated from each other. Now if the door or window be opened, the wedge tongue d¹⁰ will be withdrawn and the spring plunger d⁴ will be pressed forward against the spring d², completing the circuit and sounding an alarm.

Now to prevent burglar alarms from being sounded, whenever the doors and windows are opened by the proper person, the cut out switch s' is provided on the inside of the door or window. This should be turned off the first thing in the morning, and closed the last thing at night.

It will be evident that this system of burglar alarms would also furnish information to the main office or other portions of the establishment as to whether the watchman was going his rounds faithfully, and at what time any given shop, house or store was opened or closed.

As a check on the watchman a chronograph may be placed at the central station and connected to each circuit.

Any form of thermostat wherein the circuit is closed by heat may be employed, but the form of thermostat shown at K in the lower story of the house H^3 and in detail in Fig. 6, is preferred. In this thermostat two metallic pieces k connected to the wires 36 and r³⁶, respectively, are pivoted in an insulating frame k', and are held apart by a fusible strip k⁴ mounted on the studs k³ of the insulating blocks k² which are secured to the said legs. The legs may be allowed to fall together by their own weight after the fusible piece k⁴ has melted, or they may be drawn together by a spring k⁵. The lower ends of the legs k are preferably bent as shown, and may be denoted where they are to come together so that scales of rust, grease, &c., that might accumu-

late on plane surfaces and prevent electrical connection may be pierced or broken by the points of the dentations, and thus good contact be obtained. For ordinary purposes the fusible piece k^4 should be made of fusible metal or other substances melting at about 150° Fahrenheit; but when the thermostat is used in cold storage places, a piece of tallow or spermaceti would be a satisfactory substitute for the fusible metal.

While batteries are referred to throughout the specification, it will be evident that part of the current used in an electric lighting or power system may be used in place of each of the batteries, which current would only flow when the circuit was completed as hereinbefore described. It will thus be seen that the improved system affords a cheap, convenient, and reliable method of making electrical signals on any circuit arranged as herein described, and for sounding fire and burglar alarms.

It will be evident that the system of wiring is exceedingly simple, especially when the return current to the central station is carried to the earth.

It will also be evident that many modifications would readily suggest themselves to any one skilled in the art, which could be used without departing from the spirit of the invention.

What is claimed as new is—

1. A system of electrical fire alarms comprising two continuous conductors insulated from each other, a plurality of sources of electricity having their terminals connected to each of the said continuous conductors, and forming a bridge between the said conductors, an electrically operated signaling device placed in each of the said bridges, and a thermostat for electrically connecting said conductors, and so operating all of said signaling devices, substantially as and for the purposes described.

2. A system of electrical burglar alarms comprising two continuous conductors insulated from each other, a plurality of sources of electricity having their terminals connected to each of the said continuous conductors, and forming a bridge between the said conductors, an electrically operated signaling device placed in each of the said bridges, a contact making device attached near and operated by, an opening door or window for electrically connecting said conductors, and so operating all of said signaling devices, substantially as and for the purposes described.

3. A system of electrical alarms comprising

two continuous conductors insulated from each other, a plurality of sources of electricity having their terminals connected to each of the said continuous conductors, and forming a bridge between the said conductors, an electrically operated signaling device placed in each of the said bridges, and thermostats and contact making devices for sounding burglar alarms placed between the said conductors and adapted to make electrical connection between the said conductors, substantially as and for the purposes described.

4. A system of electrical alarms comprising two continuous conductors insulated from each other, a plurality of sources of electricity having their terminals connected to each of the said continuous conductors, and forming a bridge between the said conductors, an electrically operated signaling device placed in each of the said bridges, a switch adapted to cut out one of said signaling devices and at the same time to electrically connect said continuous conductors, and an adjustable contact piece adapted to engage said switch and so put back into electrical connection said signaling device so cut out, if desired, substantially as and for the purposes described.

5. In an apparatus of the character described, the combination with two continuous conductors insulated from each other and bridged by wires leading from the terminals of a source of electricity, with electrically operated signals contained in the said bridges, of the switch S^2 forming part of one of said bridges and connected to one of said continuous conductors, the contact piece s^6 with which said switch is in contact when said bridge is closed, the contact piece s^5 electrically connected to the other of said continuous conductors and adapted to be in contact with said switch when said bridge is open, and the adjustable contact piece s^9 electrically connected to said contact piece s^6 , and adapted to be thrown into or out of connection with said switch when it is in contact with the contact piece s^5 , substantially as and for the purposes described.

In testimony whereof we affix our signatures in presence of two witnesses.
